TILTED CONTAINER

George R. Ericson, Kirkwood, Mo., assignor to
American Car and Foundry Company, New
York, N. Y., a corporation of New Jersey

Application April 24, 1950, Serial No. 157,753

11 Claims. (Cl. 302—57)

1

This invention relates to containers in general and in particular to containers for the shipment of granulated or pulverulent material and which are adapted to be discharged by means of a pneumatic or gaseous pressure. Containers as heretofore built have been provided with at least one end of conical form in order that the material will move by gravity to the point of discharge. Such containers are costly to fabricate and require excessive bracing in order to withstand the pressures utilized during discharge. It is an object, therefore, of the present invention to provide a container having both ends of substantially identical formation and joined by a cylindrical shell.

A further object of the invention is the provision of a container of the pressure type which is mounted on its supporting base so that the area on which pulverulent material might rest is reduced to a minimum.

A still further object of the invention is the provision of a pressure type container for pulverulent material which is mounted on a base substantially elliptical in cross-section.

A yet further object of the invention is the provision of a pressure type container mounted on a base structure and having discharge outlets so arranged that discharge may be made from either side.

These and other objects of the invention will be apparent to persons skilled in the art from a study of the following description and accompanying drawings, in which

Fig. 1 is an elevational view of the improved tilted container:

Fig. 2 is a plan view of the improved container with certain parts left off to avoid confusing detail:

Fig. 3 is an end view of the improved tilted container:

Fig. 4 is a sectional view taken substantially on line 4-4 of Fig. 2 having the combined discharge nozzles and valves in place.

Fig. 5 is a fragmentary perspective view disclosing the parts in condition to discharge pulverulent or other material, and

Fig. 6 shows a fragmentary diagram of the outlet connection and valves therefor.

Referring now to the drawings in detail it will be seen that the container is made with a head portion A and base portion B welded or otherwise secured to a cylindrical central portion C. The head and base portions A and B are preferably identical in form so that they may be made on the same die. The head portion A has

2
an opening cut therein and this opening is reinforced by an angle or other shaped frame 2 to which can be fastened a pressure type lid 4 secured in place by a plurality of swing bolts or other means 6. The ends A and B have the major portion formed on a relatively large radius of curvature, with the edges merging through sharply curved corners into the straight flanges by means of which the ends are secured to the cylindrical portion C.

15 A cylindrical container of the type just described when tilted so that its longitudinal axis is inclined with respect to the vertical will produce a container having only a very small portion of the bottom sloped less than the angle of repose of the pulverulent material, which may be placed in the container. In order to hold the container in the tilted position shown, a skirt or supporting wall 10 of elliptical form is welded or otherwise secured to the cylindrical portion C and to the sharply curved corners 8 of both the head A and base B. In other words, the elliptical form base has the region adjacent the ends of its minor axis welded to the cylindrical portion C, while the areas in the region of its major axis are secured to the curved corners 8 of the head A and bottom B. The height of the supporting skirt may be reduced if desired, but in any case it will of necessity have to be attached, or will directly support both the bottom and the cylindrical part C. The lower edge of the elliptical supporting skirt is preferably stiffened by an angle 12 extending continuously around the bottom edge and providing added bearing area in cases where the container will be resting on wood or other structures. The container and its supporting structure may be lifted onto any suitable type of vehicle or from the vehicle onto any suitable supporting surfaces by means of suitable handling mechanism attached to the lifting eyes 14.

In order to discharge the tilted container, pipes 20 extend through the elliptical skirt from either side in the area of the minor axis of the elliptical skirt and these pipes have their inner ends projecting through openings cut in the lowermost portion of the curved corner 3 of the bottom B and flanged at 26 to facilitate their attachment to the container wall and associated parts. These pipe flanges 26 may be securely welded or otherwise secured to the container and have their inner ends cut off so as to conform to the inner surface of the container, all as clearly shown in Figs. 4 and 5. With the container tilted as shown 55 all portions of the cylindrical shell C will be

sloped with respect to the horizontal at angles equal to or greater than the angle of inclination of the container axis. Also, all portions of the bottom B will be sloped with respect to the horizontal at angles equal to or greater than the inclination of the bottom as shown in Fig. 1. With the container as shown the axis is sloped at an angle of forty-five degrees, accordingly substantially all portions of the base B and cylindrical shell C will readily permit movement of pulverulent material downward toward the discharge pipes 20. Some material may tend to lie in the lowermost portion of the sharply curved part 8 and this material may be moved toward the discharge outlet pipes by means of nozzles 22 fastened in the container in the zone of the curved corners and attached to be fed by air through pipes 24 extending exterior of the container shell.

The outer ends of discharge pipes 20 are flanged as at 25 and adapted to receive bolts or other means 28 by means of which a flanged closure plate 30 may be securely fastened to the pipe flange 26. The flanged closure plate 30 is welded or otherwise secured to a pipe 32 telescoping within pipe 20 and having an outside diameter but slightly smaller than the inside diameter of discharge pipes 20. The outer ends of the pipes 32 are closed by means of the closure plate 36 which is provided with a threaded opening 33 which is normally closed by plug 34. The plug 34 protects the threads of the opening 33 and inasmuch as only one nozzle 32 is used during unloading, provides a seal for the inactive nozzle. To connect one of the nozzles 32 with a suitable source of compressed air a valved union is illustrated at 35, having outer threaded inlet 35a and flanged outlet end 35b, the latter flange to be clamped or bolted to the flanges 26 and 30 after removal of the plug 34. A plug valve 37 controls the flow of compressed air to the nozzles 32, and another valve 37a controls the passage of air through the lateral port 39 in instances when the nozzles 22 are to be utilized, connection between the lateral port 39 and nozzle 22 being by means of a flexible hose 22a. The inner ends of pipes 32 are reduced in diameter to provide a nozzle tip 36, which nozzle tip is adapted to discharge into the opposed discharge pipe 20. The ends of these nozzles when in normal position as shown in Fig. 4 have their ends closely adjacent to each other and one of the nozzles has preferably secured thereto a flared extension 38 adapted to fit over the opposed nozzle and prevent entrance of pulverulent material to the nozzle interior during shipment. Each nozzle is also preferably provided with a plurality of fine holes 40 drilled through the pipe 32 at different angles for the purpose of aerating or disturbing the pulverulent material in the zone of the discharge nozzle.

In operation the container will be filled through the door or manhole 4 and transported with the nozzles in place as shown in Fig. 4, thus the nozzles will always be shipped with the container and will serve as plugs or valves preventing pulverulent material from packing or becoming hardened in the discharge pipes 20. Upon arrival at the point of discharge one of the pipes 32 will be removed leaving the parts in the condition shown in Fig. 5. A receiving pipe or other structure will then be bolted to the flange 26 for carrying away material from the container. Air or other gaseous material will then be fed through the pipe 32 and its nozzle as shown at the left hand side of Fig. 5 by a connection such

as shown in Fig. 6, and this air or gaseous material will aerate or fluff the material due to the small holes 40, while the main blast from the nozzle will carry the material out of the opposed discharge pipe 20. Normally, the nozzles 22 will not be needed except at the time of final discharge or cleaning up of the container interior. Turning gaseous material into these nozzles will blast the small amount of remaining material off the walls and into position to be picked up by the blast of the nozzle formed on pipe 32.

While the container has been described more or less in detail with specific reference to one tilted position, it will be understood that various modifications and rearrangements of parts other than those shown and described may be made without departing from the scope of my invention as defined by the appended claims.

What is claimed is:

1. A closed container for the shipment of pulverulent material comprising a cylindrical head portion, a cylindrical base portion, a central cylindrical portion joining the head and base portions, and a plate metal skirt shrouding the lower portion of the container and having its upper edge secured to each of said portions to retain the container in a tilted position.

2. A closed container for the shipment of pulverulent material comprising a cylindrical head portion, a cylindrical base portion, a central cylindrical portion joining the head and base portions, and a plate metal skirt shrouding the lower portion of the container and having its upper edge secured to each of said portions to retain the container in a tilted position, said supporting skirt being substantially elliptical in cross-section.

3. A closed container for the shipment of pulverulent material comprising a cylindrical head portion, a cylindrical base portion, a central cylindrical portion joining each of said portions to form a pressure vessel, a pair of discharge pipes secured to said container adjacent the juncture of said central portion and base portion and having their axes substantially in alignment, and means normally closing said discharge pipes and having the inner ends projecting into the container, said inner ends being formed with ejector tips whereby pulverulent material may be blown out of the container through the opposed discharge pipe.

4. A closed container for the shipment of pulverulent material comprising a cylindrical head portion, a cylindrical base portion, a central cylindrical portion joining each of said portions to form a pressure vessel, a pair of discharge pipes secured to said container adjacent the juncture of said central portion and base portion and having their axes substantially in alignment, and an ejector nozzle removably mounted in and closing each of said discharge pipes and having their inner ends substantially abutting intermediate the ends of said discharge pipes.

5. A closed container for the shipment of pulverulent material comprising a cylindrical head portion, a cylindrical base portion, a central cylindrical portion joining each of said portions to form a pressure vessel, a pair of discharge pipes secured to said container adjacent the juncture of said central portion and base portion and having their axes substantially in alignment, an ejector nozzle removably mounted in and closing each of said discharge pipes and having their inner ends substantially abutting intermediate the ends of said discharge pipes, and means clos-

ing the ends of said ejector nozzles when in position within the discharge pipes to prevent ingress of pulverulent material.

6. A closed container for the shipment of pulverulent material comprising a cylindrical head portion, a cylindrical base portion, a central cylindrical portion joining each of said portions to form a pressure vessel, supporting means retaining the container in a tilted position with the longitudinal axis inclined to an angular position substantially equal to or greater than the angle of repose of the pulverulent material, a pair of discharge pipes entering and secured to the container adjacent the lowermost portion thereof, said pipes extending to either side of the container substantially tangential to the lowermost edge of the cylindrical base portion and having their axes substantially in alignment, and ejector means normally closing said discharge pipes and preventing entrance of material into said pipes.

7. A closed container for the shipment of pulverulent material comprising a cylindrical head portion, a cylindrical base portion, a central cylindrical portion joining each of said portions to form a pressure vessel, supporting means retaining the container in a tilted position with the longitudinal axis inclined to an angular position substantially equal to or greater than the angle of repose of the pulverulent material, a pair of discharge pipes entering and secured to the container adjacent the lowermost portion thereof, said pipes extending to either side of the container substantially tangential to the lowermost edge of the cylindrical base portion and having their axes substantially in alignment, and ejector means normally closing said discharge pipes and preventing entrance of material into said pipes, said ejector means being selectively removable from the discharge pipes whereby the remaining ejector may be utilized to move material through the discharge pipe opened by removal of the selected ejector means.

8. A closed container for the shipment of pulverulent material comprising a cylindrical head portion, a cylindrical base portion, a central cylindrical portion joining each of said portions to form a pressure vessel, supporting means retaining the container in a tilted position with the longitudinal axis inclined to an angular position substantially equal to or greater than the angle of repose of the pulverulent material, a pair of discharge pipes entering and secured to the container adjacent the lowermost portion thereof, said pipes extending to either side of the container substantially tangential to the lowermost edge of the cylindrical base portion and having their axes substantially in alignment, and ejector means normally closing said discharge pipes and preventing entrance of material into said pipes, said ejector means having the inner ends thereof terminating adjacent a vertical plane through the longitudinal axis of the tilted container.

9. A closed container for the shipment of pulverulent material comprising a cylindrical head

portion, a cylindrical base portion, a central cylindrical portion joining each of said portions to form a pressure vessel, supporting means retaining the container in a tilted position with the longitudinal axis inclined to an angular position substantially equal to or greater than the angle of repose of the pulverulent material, a pair of discharge pipes entering and secured to the container adjacent the lowermost portion thereof, said pipes extending to either side of the container substantially tangential to the lowermost edge of the cylindrical base portion and having their axes substantially in alignment, and ejector means normally closing said discharge pipes and preventing entrance of material into said pipes, said ejector means including nozzles with the inner open ends thereof terminating adjacent a vertical plane through the longitudinal axis of the tilted container and also including a plurality of small openings located adjacent the line of intersection of the associated discharge pipe and container.

10. A closed container for the shipment of pulverulent material comprising a cylindrical head portion, a cylindrical base portion, an elongated central cylindrical portion joining the head and base portions, and a plate metal skirt shrouding the lower portion of the container and having its upper edge secured to the base portion and to said elongated central cylindrical portion substantially throughout the height of the latter to retain the container in a tilted position.

11. A closed container for the shipment of pulverulent material comprising a cylindrical head portion, a cylindrical base portion, an elongated central cylindrical portion joining the head and base portions, and a plate metal skirt shrouding the lower portion of the container and having its upper edge secured to the base portion and to said elongated central cylindrical portion substantially throughout the height of the latter to retain the container in a tilted position, said supporting skirt being substantially elliptical in cross-section and edge welded to said portions.

GEORGE R. ERICSSON.
